UNITED STATES PATENT OFFICE.

CHARLES R. WILSON, OF CHARLESTON, WEST VIRGINIA.

DESIGN FOR A HIGHWAY-SIGN.

59,698.

Specification for Design.

Patented Nov. 15, 1921.

Application filed February 11, 1921. Serial No. 444,270. Term of patent 7 years.

To all whom it may concern:

Be it known that I, CHARLES R. WILSON, a citizen of the United States, residing at Charleston, in the county of Kanawha and State of West Virginia, have invented a new, original, and ornamental Design for Highway-Signs, of which the following is a specification, reference being had to the accompanying drawing, forming part thereof.

Figure 1 is a top plan view of the sign.

Fig. 2 is a front elevation of the sign.

When the sign is displayed by the side of a highway, a portion of its lower end will be hidden, being embedded in the earth.

As the lettering to be displayed on this sign may be varied and is no part of the invention, it is omitted from the drawings.

I claim:

The ornamental design for a highway sign, as shown.

CHAS. R. WILSON.
